TYPEWRITING MACHINE

George F. Handley, Glendale, N. Y., assignor to
 Royal Typewriter Company, Inc., New York,
 N. Y., a corporation of New York

Application September 5, 1934, Serial No. 742,789

11 Claims. (Cl. 197—165)

This invention relates to improvements in typewriting machines generally and in machines of analogous arts, although more particularly to improvements in automatic ribbon reversing mechanisms such as is disclosed in my Patent 1,570,218, January 19, 1926.

The invention relates broadly to devices for reversing the feed of the ribbon when one spool is substantially empty, and more specifically to a reversing means operated by a projection carried by the ribbon. It is illustrated in connection with the portable Royal typewriter, but it is to be noted that it can be employed with other typewriting machines or with other types of machines wherein a ribbon is fed step by step through the operation of keys or equivalent parts.

Among the several objects of my invention are to provide a ribbon reversing mechanism in which the ribbon will begin a positive reverse winding movement immediately upon the reversing mechanism becoming effective and without any slack or loop being formed in the ribbon between the ribbon guide finger and the spool; to provide means for preventing the jamming of the reversing mechanism should any one either intentionally or unintentionally move the guide fingers inwardly, and to provide such a reversing mechanism which is composed of comparatively few parts and is therefore not only cheap to manufacture but is durable in operation.

In the drawings:—

Figure 1 is a sectional front elevation of a ribbon reverse mechanism with certain parts omitted, the mechanism being shown in operating position.

Figure 2 is a horizontal sectional view taken on the irregular line 2—2 of Figure 1 looking in the direction of the arrows.

Figure 3 is a fragmentary top plan view of the construction shown in Figure 1 with certain parts omitted.

Figure 4 is a view similar to Figure 1 but showing some of the associated parts in advanced working positions.

Figure 5 is a detail elevation, partly in section, showing the ribbon reversing elements in their reversed positions.

Figure 6 is a detail sectional view taken on the line 6—6 of Figure 3 looking in the direction of the arrows, the parts being in their normal positions.

Figure 7 is a similar view to Figure 6 but showing the ribbon guide at the extreme inner end

of its movement and the reversing pawl still in its effective position.

Figure 8 is a view similar to Figure 6 but showing the reversing pawl in a position just after it has started to return to its initial position.

Figure 9 is an enlarged perspective view showing the spiral wheel and the associated rotary camming element, together with the lower end of the reversing pawl in effective engagement with said wheel.

Figure 10 is a perspective view of the thread guide and arm.

Figure 11 is a perspective view of the reversing pawl together with the interponent which is pivoted thereon.

Figure 12 is an enlarged detail front elevation of the pawl and worm in operative engagement.

Figure 13 is a detail elevation showing a modified form of interponent.

Referring to the accompanying drawings, 5, 5 indicate the side walls of the main frame of a type writing machine. Attached to the inner faces of these walls are vertical brackets A, A, each bracket including a rearwardly extending wall 6 having upper and lower inwardly extending horizontal arms 7 and 8. Journaled in each pair of arms 7 and 8 is a vertically disposed spool shaft 9 having mounted on the upper end thereof a ribbon spool 10. A ribbon 11 is alternately wound on the spool, means being provided to automatically reverse the rotation of these spools in order to effect this alternate winding of the ribbons. Journaled in the brackets A, A below the spool shafts 9 is a driving shaft 12 which is not only free to rotate but is also free to be reciprocated longitudinally. Fixed to the lower end of each spool shaft 9 is a beveled gear 13. Fixed to the driving shaft 12 are beveled gears 14, 14 which are adapted to alternately engage the gears 13, 13 and thereby effect alternate rotations of the ribbon spools 10. The driving shaft 12 is intermittently rotated through the medium of a ratchet wheel 15 fixed thereon and a cooperating pawl 16 which is actuated from the universal bar 17 whereby the shaft will be rotated step by step at each depression of a type bar key lever. Adjacent one of the beveled gears 14, the shaft 12 is provided with a fixed collar 18 having two peripheral grooves 19 and 20 therein. A spring pressed detent 21 is pivoted to the lower arm 8 of the associated bracket A and cooperates with the grooves 19 and 20 to hold the shaft 12 in either of its longitudinal or endwise adjustments, whereby one of the beveled gears 14 will

20

45

50

55

be held in engagement with its associated beveled gear 13 while at the same time the other gear coupling 13, 14 will be held in disengaged relation. In order to reverse the rotations of the 5 spools 10, the shaft 12 is automatically reciprocated endwise, the spring detent 21 being cammed from one groove 19 or 20 into the other of said grooves. This driving shaft 12 is automatically reciprocated endwise by the movement of the ribbon 10 as it is being unwound from each spool by the following mechanism:—

Fixed to the ribbon 11 adjacent each end thereof is a button or projection 22 which as the ribbon is nearly fed off the associated spool, engages a ribbon guide 23 and moves the latter in a direction away from the spool. The guide 23 is attached to the inner end of a horizontal arm 24 which is mounted on the bracket A for a straight line movement in a horizontal plane, the 15 inner end of the arm 24 being provided with a longitudinal slot 25 through which a stud or screw 26 passes into a part of the bracket A, the outer end of the arm 24 being slidably supported in an opening 27 formed in the bracket A. It 20 will be noted that the ends of the slot 25 serve as stops to limit the sliding movement of the ribbon guide. The inner end of the slot 25 is normally engaged with the associated stud 26 and consequently as the ribbon unwinds the button or projection 22 will engage the guide 23 and thereby move said guide together with its arm 24 inwardly in a straight line and in a horizontal plane. Rigidly connected to the guide arm 24 and preferably formed integral therewith and extending downwardly therefrom is a trailing cam 28 which consists of a straight inclined edge disposed at an angle of less than 30° to the horizontal. Slidably supported for vertical movements in guide openings in the bracket arms 7 and 8 is a reversing 25 pawl 29, said pawl including an upwardly extending guide arm 30. A coil spring 31 has one end connected to the pawl 29 and the other end to the upper bracket arm 7 and functions to yieldably retain the pawl in its upper or inactive position. Associated with each reversing pawl 29 is 30 a helical toothed wheel or worm 32 which is fixed to the driving shaft 12 below said pawl. The pawl 29 in horizontal cross section is inclined relative to the axis of the driving shaft 12 in order 35 to register with the inclined teeth 32a of the wheel 32, the opening in the lower horizontal bracket arm 8 being correspondingly inclined to receive the pawl 29 and maintain the same in its angular relation while being reciprocated vertically.

It will, therefore, be seen that when the pawl 29 is moved downwardly into engagement with the teeth 32a of the wheel 32 the intermittent rotation of the latter will through its cooperation 40 with the pawl 29 cam the driving shaft 12 outwardly to effect an engagement between the associated bevel gears 13 and 14 and thereby reverse the direction of rotation of the associated spool 10. The distance of travel of the pawl 29 45 is considerably less than the travel of the ribbon guide 23, and in order to positively move the pawl 29 downwardly into engagement with the teeth of the associated wheel 32, I have provided a yieldable interponent 33 which is pivoted intermediate 50 its ends as at 34 to the upwardly extending guide arm 30 of said pawl 29. The interponent 33 is in the nature of a lever and is centrally formed on its upper edge with a concentric portion 35 which merges with an eccentric portion 36. This 55 interponent is located directly below the upper

bracket arm 7 and in the normal position of the parts the concentric edge 35 of said interponent is held in yieldable and slidable contact with the lower face of upper bracket arm 7 by means of the coil spring 31. An arm 38 which depends 5 from the forward end of the interponent terminates in a laterally extending stop finger 39 which normally engages the forward edge of the guide arm 30 of the reversing pawl 29. The rear end 10 of the interponent forms a cam finger 40 which 10 projects under and is at all times held in sliding contact with the cam 28 on the guide arm 24.

In operation, as the ribbon unwinds from a spool 10 the button or projection 22 which is fixed to and travels with the ribbon engages the ribbon 15 guide 23 and moves the latter inwardly in a straight horizontal line. During this inward movement of the ribbon guide 23, the cam 28 which is carried by the guide arm 24 is caused to depress the cam finger 40 of the interponent 20 33 and thereby swing the latter against the tension of its spring 31. During this swinging movement of the interponent the eccentric edge 36 thereof slidably engages the upper bracket arm 7 which, being fixed, functions as an abutment 25 30 whereby the pawl 29 will be depressed against the tension of its spring 31 into engagement between a pair of teeth of the associated spiral wheel 32 and thereby cam the driving shaft 12 endwise and effect a coupling of the associated 35 bevel gears 13, 14. Inasmuch as the amount of intermittent movement imparted to the ribbon may vary to a slight extent due to the tightness or looseness with which the ribbon is wound on the spool, the parts have been timed and constructed so that the pawl 29 will become active before the ribbon guide 23 reaches the limits of its inward movement under the influence of the ribbon button or projection 22.

As soon as the reversing driving connection between bevel gears 13, 14 has been rendered effective, the ribbon guide 23 will be returned to its initial position. This return movement of the ribbon guide is effected slowly and without forming a bow or slack in the ribbon between the button 22 and the spool 10. This condition is brought about by reason of the angle of the cam 28 being relatively small, it being preferably less than 30° as stated. Consequently, the cam will be returned by gravity plus a slight assistance by the 40 spring 31, at a much slower rate of speed than if a cam of a larger angle were employed. This is very important because it avoids the necessity of taking up such slack prior to the initial starting of the reverse movement of the ribbon. Thus 45 the reverse movement of the ribbon starts practically simultaneously with the coupling of the two reverse bevel gears 13, 14 and consequently the ribbon will not receive a plurality of type impacts at a single point. As soon as the bevel 50 gears 13, 14 are engaged, the spiral wheel 32 will become disconnected from the pawl 29 and immediately thereafter the ribbon guide 23 will be cammed to its initial position, due to the spring 31 exerting an upward pull on the pawl 29 whereby the cam finger 40 will ride along the cam 28 and slowly move the guide 23 inwardly to its initial position. By reason of the cam 28 being disposed at an angle less than 30° to the horizontal, this inward movement of the guide will 55 be sufficiently slow to avoid the possibility of forming a loop or slack in the ribbon between the button 22 and the spool.

I have also provided means which not only initially starts the reversing pawl 29 in its return 60

or upward movement but also functions to avoid the pawl interfering with the endwise movement of the driving shaft 12 should any one manually move both ribbon guides 23 inwardly simultaneously. To this end, I have attached rigidly to the inner face of each spiral wheel 32 a camming element 41 having a smooth concentric periphery 42 and an inner beveled face 43, the periphery 42 being spaced from the spiral wheel or worm 32 and the bevel or cam inner face 43 being located therebetween. The diameters of the worm 32 and the camming element 41 are substantially equal. As the driving shaft 12 begins to move endwise under the conjoint action of the reversing pawl 29 and the spiral gear 32, the latter will gradually be moved from engagement with the pawl and the latter will be gradually moved into engagement with the bevel or circular cam 43 and thereby impart an initial lifting movement to the reverse pawl 29. Should any one move the ribbon guides 23 inwardly simultaneously, one of the pawls would be caused to engage the associated spiral wheel 32 while the other pawl would be moved downwardly below the roots of the teeth 32^a of the associated wheel 32 and thereby prevent the shaft 12 from being moved endwise, but by providing the cam element 41 as above described, I have provided means for preventing the reverse pawl 29 from being moved downwardly to block the return movement of the driving shaft 12 as the pawl will engage the concentric surface 42 of the element 41 and thereby retain the pawl above the roots of said teeth.

Should the pawl 29 be moved downwardly into very tight contact with a tooth root on the wheel 32, which might occur if the ribbon guide 23 is moved too far by hand or by the ribbon button 22, the pawl and the wheel will jam and the shaft 12 will not be shifted. To avoid this condition, and thereby insure the proper reversing of the ribbon, I have provided a modified form of interponent as shown in Figure 13. This interponent is provided with an eccentric edge 45 which normally engages the abutment 7, and with a concentric edge 46 which merges with the eccentric edge 45, the concentric edge 46 engaging the abutment 7 when the pawl 29 is located just above the root of the teeth 32^a of the wheel 32. This further rocking movement of the interponent will not transmit further downward movement to the pawl. The interponent is provided with a cam finger 40^a for engagement with the cam 28, and with an arm 38^a which terminates in a stop 39^a. A coil spring 47 which is connected to the arm 38^a and to the guide arm 30 of the pawl 29 functions to return the interponent to its initial position.

I claim:

1. A ribbon reversing mechanism for typewriting machines or the like comprising a ribbon spool shaft, a longitudinally movable driving shaft normally disconnected from the spool shaft, and means including a cam shiftable horizontally by the ribbon for moving the driving shaft longitudinally to thereby effect a driving connection between the spool shaft and the driving shaft.

2. A ribbon reversing mechanism for typewriting machines or the like comprising a ribbon spool shaft, a driving shaft normally disconnected from the spool shaft and mounted for longitudinal movement for operative connection with said spool shaft, a normally disengaged pawl and worm for giving the driving shaft said longitudinal movement, the worm being fixed to the driv-

ing shaft, and ribbon actuated means for engaging the pawl with the worm including a guide movable in one direction by the ribbon during the unwinding of the latter, and a cam shiftable horizontally with the guide located between the ribbon guide and the pawl for moving the latter into engagement with the worm. 5

3. A ribbon reversing mechanism for typewriting machines or the like comprising a ribbon spool shaft, a driving shaft normally disconnected from the spool shaft and mounted for longitudinal movement for operative connection with said spool shaft, a normally disengaged pawl and worm for giving the driving shaft said longitudinal movement, the worm being fixed to the driving shaft, said pawl being movable in a straight vertical path, a spring for normally retaining the pawl out of engagement with the worm, and ribbon actuated means for engaging the pawl with the worm including a guide slidably mounted for a straight line horizontal movement by the ribbon during the unwinding of the latter, and a cam shiftable horizontally with the guide located between the ribbon guide and the pawl for moving the latter against the tension of its spring into engagement with the worm. 10

4. A ribbon reversing mechanism for typewriting machines or the like comprising a ribbon spool shaft, a driving shaft normally disconnected from the spool shaft and mounted for longitudinal movement for operative connection with said spool shaft, a normally disengaged pawl and worm for giving the driving shaft said longitudinal movement, the worm being fixed to the driving shaft, and ribbon actuated means for engaging the pawl with the worm including a guide movable in one direction by the ribbon during the unwinding of the latter and provided with a cam, and a yieldable interponent pivoted on the pawl and engageable with the cam for moving the pawl into engagement with the worm. 20

5. A ribbon reversing mechanism for typewriting machines including a main frame, a bracket mounted on the frame and including an abutment, a vertical ribbon spool shaft journaled in the bracket, a horizontal driving shaft normally disconnected from the spool shaft and supported on the frame for longitudinal movement for operative connection with the spool shaft, a normally disengaged pawl and worm for giving the driving shaft said longitudinal movement, the pawl being mounted in the bracket for vertical movements and the worm being fixed to the driving shaft, a spring for normally retaining the pawl out of engagement with the worm, and ribbon actuated means for engaging the pawl with the worm including a guide movable in one direction by the ribbon during the unwinding of the latter, an inclined trailing cam movable with the guide, and a yieldable interponent pivoted on the pawl and having sliding contact with the abutment and with the cam. 30

6. A ribbon reversing mechanism for typewriting machines including a main frame, a bracket mounted on the frame and including an abutment, a vertical ribbon spool shaft journaled in the bracket, a horizontal driving shaft normally disconnected from the spool shaft and supported on the frame for longitudinal movement for operative connection with the spool shaft, a normally disengaged pawl and worm for giving the driving shaft said longitudinal movement, the pawl being mounted in the bracket for vertical movements and the worm being fixed to the driving shaft, and ribbon actuated means for 40

- engaging the pawl with the worm including a guide movable in one direction by the ribbon during the unwinding of the latter, an inclined trailing cam movable with the guide, a yieldable interponent pivoted on the pawl and having sliding contact with the abutment and with the cam, and a coil spring connecting the pawl and the bracket for yieldingly retaining the pawl against movement and for retaining the interponent in sliding contact with the abutment.
7. A ribbon reversing mechanism for typewriting machines or the like comprising a ribbon spool shaft, a driving shaft normally disconnected from the spool shaft and mounted for longitudinal movement for operative connection with said spool shaft, a normally disengaged pawl and worm for giving the driving shaft said longitudinal movement, the worm being fixed to the driving shaft, said pawl being movable in a straight vertical path, a spring for normally retaining the pawl out of engagement with the worm, ribbon actuated means for moving the pawl into engagement with the worm, means for returning the pawl to its normal position, and means for retaining the pawl against being moved downwardly alongside of the worm to a point below the roots of the teeth of the worm.
8. A ribbon reversing mechanism for typewriting machines or the like comprising a ribbon spool shaft, a driving shaft normally disconnected from the spool shaft and mounted for longitudinal movement for operative connection with said spool shaft, a normally disengaged pawl and worm for giving the driving shaft said longitudinal movement, the worm being fixed to the driving shaft, said pawl being movable in a straight vertical path, a spring for normally retaining the pawl out of engagement with the worm, ribbon actuated means for moving the pawl into engagement with the worm, means for returning the pawl to its normal position, and means for retaining the pawl against being moved downwardly alongside of the worm to a point below the roots of the teeth of the worm, said preventing means comprising an element fixed to the driving shaft adjacent the worm and having a smooth concentric periphery located in the path of movement of the pawl, the diameter of the element being substantially equal to the diameter of the worm, said element being formed with a downwardly, inclined circular cam located between said smooth peripheral surface and the gear for positively starting the pawl in its return movement.
9. A ribbon reversing mechanism for typewriting machines or the like comprising a ribbon spool shaft, a driving shaft normally disconnected from the spool shaft and mounted for longitudinal movement for operative connection with said spool shaft, a normally disengaged pawl and worm for giving the driving shaft said longitudinal movement, the worm being fixed to the driving shaft, and ribbon actuated means for engaging the pawl with the worm including a guide movable in one direction by the ribbon during the

unwinding of the latter, cam means located between the ribbon guide and the pawl for moving the latter into engagement with the worm, a spring for returning the pawl to its normal position, and cam means mounted on the shaft for positively starting the pawl in its return movement.

10. A ribbon reversing mechanism for typewriting machines or the like comprising a ribbon spool shaft, a driving shaft normally disconnected from the spool shaft and mounted for longitudinal movement for operative connection with said spool shaft, a normally disengaged pawl and worm for giving the driving shaft said longitudinal movement, the worm being fixed to the driving shaft, said pawl being movable in a straight vertical path, a spring for normally retaining the pawl out of engagement with the worm, ribbon actuated means for moving the pawl into engagement with the worm, means for returning the pawl to its normal position, and means for retaining the pawl against being moved downwardly alongside of the worm to a point below the roots of the teeth of the worm, said preventing means comprising an element fixed to the driving shaft adjacent the worm and having a smooth concentric periphery located in the path of movement of the pawl, the diameter of the element being substantially equal to the diameter of the worm, said element being formed with a downwardly, inclined circular cam located between said smooth peripheral surface and the gear for positively starting the pawl in its return movement.

11. A ribbon reversing mechanism for typewriting machines including a main frame, a bracket mounted on the frame and including an abutment, a vertical ribbon spool shaft journaled in the bracket, a horizontal driving shaft normally disconnected from the spool shaft and supported on the frame for longitudinal movement for operative connection with the spool shaft, a normally disengaged pawl and worm for giving the driving shaft said longitudinal movement, the pawl being mounted in the bracket for vertical movements and the worm being fixed to the driving shaft, a spring for normally retaining the pawl out of engagement with the worm, and ribbon actuated means for engaging the pawl with the worm including a guide movable in one direction by the ribbon during the unwinding of the latter, an inclined trailing cam movable with the guide, a yieldable interponent pivoted on the pawl and having sliding contact with the abutment and with the cam, said interponent having an eccentric edge normally contacting the abutment and a merging concentric edge engageable with the abutment after the pawl engages the teeth of the worm and preventing the pawl from contacting the root of the worm teeth.

GEORGE F. HANDLEY.
